UNITED STATES PATENT OFFICE.

ORRIN MILO WHITMAN, OF BOSTON, MASSACHUSETTS.

DOOR-SECURER.

SPECIFICATION forming part of Letters Patent No. 371,650, dated October 18, 1887.

Application filed February 21, 1887. Serial No. 228,334. (No model.)

To all whom it may concern:

Be it known that I, ORRIN MILO WHITMAN, of Boston, in the county of Suffolk, of the Commonwealth of Massachusetts, have invented a new and useful Improvement in Door-Fasteners; and I do hereby declare the same to be described in the following specification, and represented in the accompanying drawings, of which—

10 Figure 1 is a front elevation, and Fig. 2 a transverse section, of part of a door and its casing with my improved fastening applied thereto, the nature of it being defined in the claim hereinafter presented. Fig. 3 is a front 15 elevation, and Fig. 4 a side view, of a modification in shape of that part of my invention which operates with the plate D and its curved horn or projection, as hereinafter described.

20 In the said drawings, A denotes the door, and B the casing, the connections of them being hinges C, as represented.

D is a base-plate, fastened to the casing and provided with a horn or curved projection, 25 E, formed and extending from it as indicated. F is another such base-plate, secured to the door and provided with a slotted or bow-shaped handle, G, formed as shown, and jointed or hinged to such base-plate.

30 On turning the handle upon the projection E the inner end or part, b, of the slot a of such handle will be borne against the inner curved face or portion, c d, of such projection, and in advancing thereon will cause the door to be 35 pressed rearwardly and inwardly, so as to be firmly closed in the recess of the casing.

The curve of the bearing part c d of the inner edge of the horn or projection E is not the arc of a circle whose center is at the axis 40 of the joint of the handle G, (such arc being shown in Fig. 2 at e by dotted lines,) but is angular thereto, so as to cause the door, while the handle is being moved against such bearing part, to be forced rearwardly—that is, in 45 a direction toward the part of the casing to which the door is hinged—such a movement of the door being to keep it from sticking at its front edge against the casing. In refrigerators, owing to the dampness generated or 50 changes of temperature, the doors are liable to swell and frequently to stick fast in the cas-

ing. With my improved fastening applied to a door and its casing such sticking of the door cannot easily occur. The door by means of it can be tightly closed, and can be easily opened 55 or closed, as occasion may require. The base-plates D and F have countersunk holes in them to receive the screws s, used in fastening such base-plates, one to the door and the other to the casing.

60 Instead of slotting the handle and having the curved horn to go through it when the handle is turned against such horn, I form the handle with a cylindrical projection, f, (see Figs. 3 and 4,) at its lower part, which I arrange eccentrically to the joint-pin of such handle. When the handle is turned down, the eccentric bears against the horn and acts with it to produce results such as are above described as incident to the slotted handle. The handle 65 formed or provided with the eccentric may be considered as a mechanical equivalent for the handle as made with the slot to receive and act against the horn.

70 I do not claim a door-fastener constructed 75 and applied in manner and to operate like that described in the United States Patent No. 382,495, the handle in such door-fastener being movable in a vertical plane in order to press the door laterally, whereas with my door-fastener the handle is movable horizontally, and the door is by the fastener moved toward that part of the casing to which the door is hinged, such being to prevent sliding of the door in the opposite part of the casing. In my fastening 80 there is no lug projecting laterally from a head having an eccentric axis, nor is there any keeper or catch formed with an opening or notch to receive such lug, as is the case in such patented fastening shown in said Patent No. 332,495. 90

I claim—

The door-fastener, substantially as described, composed of the base-plate D, its curved horn or projection E, the base-plate F, and the slotted handle G, such handle being hinged to 95 such base-plate F, and all being arranged and constructed and for use essentially as set forth.

ORRIN MILO WHITMAN.
